(57) **CLAIM**

The ornamental design for a display panel or screen with an animated graphical user interface, as shown and described.

DESCRIPTION

FIG. 1 is a front view of a first embodiment of a display panel or screen with a first image of an animated graphical user interface showing our new design;

FIG. 2 is a second image thereof;

FIG. 3 is a third image thereof;

FIG. 4 is a fourth image thereof;

FIG. 5 is a fifth image thereof; and

FIG. 6 is a sixth image thereof.

FIG. 7 is a front view of a second embodiment of a display panel or screen with a first image of an animated graphical user interface showing our new design;

FIG. 8 is a second image thereof;

FIG. 9 is a third image thereof;

FIG. 10 is a fourth image thereof;

FIG. 11 is a fifth image thereof; and

FIG. 12 is a sixth image thereof.

FIG. 13 is a front view of a third embodiment of a display panel or screen with a first image of an animated graphical user interface showing our new design;

FIG. 14 is a second image thereof;

FIG. 15 is a third image thereof;

FIG. 16 is a fourth image thereof;

FIG. 17 is a fifth image thereof; and

FIG. 18 is a sixth image thereof.

FIG. 19 is a front view of a fourth embodiment of a display panel or screen with a first image of an animated graphical user interface showing our new design;

FIG. 20 is a second image thereof;

(Continued)

FIG. 21 is a third image thereof;
